CLAIM

The ornamental design for the side table, as shown and described.

DESCRIPTION

FIG. 1 is a perspective view of a side table in accordance with the new design;

FIG. 2 is a front elevational view thereof;

FIG. 3 is a right side elevational view thereof, a left side elevational view being a mirror image thereof;

FIG. 4 is a top view thereof;

FIG. 5 is a perspective view of an alternative embodiment of a side table in accordance with the new design;

FIG. 6 is a front elevational view thereof;

FIG. 7 is a right side elevational view thereof, a left side elevational view being a mirror image thereof; and,

FIG. 8 is a top view thereof.

The broken lines in the drawing figures are for illustrative purposes only and form no part of the claimed design.
